UNITED STATES PATENT OFFICE

111,709

DESIGN FOR A COMBINED SUPPORTING TRAY AND POWDER PUFF DISPLAY

Joseph Levy, Brooklyn, N. Y.

Application August 28, 1937, Serial No. 71,371

Term of patent 14 years

To all whom it may concern:

Be it known that I, Joseph Levy, a citizen of the United States, residing in the city of Brooklyn, in the State of New York, have invented a new, original, and ornamental Design for a Combined Supporting Tray and Powder Puff Display, of which the following is a specification, reference being had to the accompanying drawing, forming a part thereof, in which:

Fig. 1 is a perspective view of the combined supporting tray and powder puff display showing my new design; and

Fig. 2 is an end view thereof.

I claim:

The ornamental design for a combined supporting tray and powder puff display, as shown.

JOSEPH LEVY.
